TENT

Frank M. Powers, Chicago, Ill., assignor to Powers & Company, Chicago, Ill., a corporation of Delaware

Application March 12, 1937, Serial No. 130,436

8 Claims. (Cl. 135—1)

This invention relates to improvements in tents and more especially to a tent provided with a canopy or awning. For the purpose of illustrating my invention I have here shown the same applied to an umbrella tent, although it is obvious that with slight alterations the invention may be utilized with tents of other forms and shapes.

The principal feature of my invention is the provision of means for making a pitch or water shed in the canopy or awning. As is well known, such a canopy is preferably substantially rectangular in shape and usually about horizontal. Two of its corners are attached to and supported by the tent and the other two corners are supported by two poles.

That is, the canopy is ordinarily held in substantially a horizontal position. In the ordinary canopy construction of this kind difficulty has been encountered in the past due to accumulation of rain water on the canopy, causing it to sag, with consequent leakage and deterioration of the fabric. In my improved construction means are provided for raising and supporting central portions of the canopy to provide a sort of peak, peaks, or ridge at a slight elevation to cause more effective drainage of water from the canopy.

Other features and advantages will appear more fully as I proceed with my specification.

In those forms of device embodying the features of my invention shown in the accompanying drawings, Fig. 1 is a view in side elevation, Fig. 2 is a top plan view, and Figs. 3 and 4 are views similar to Figs. 1 and 2 respectively showing a modified form.

As shown in the drawings, 10 indicates in general a tent of the umbrella type, employing a conventional construction utilizing a center pole 11 with a suitable frame 12 at the junction of the roof and side walls. The details of the tent construction need not be shown as they form no part of the present invention; and it is to be understood that my invention is applicable to many types of tents of various constructions.

13 indicates a substantially rectangular canopy or awning supported in a horizontal position in front of the tent. In general, this awning is held in a conventional manner by fastening its rear corners 14 and 15 to the corners of the tent. For example, attachment may be made to the pins 16 and 17 respectively, carried by the frame 12 of the tent proper. The outer corners of the canopy 13 may be held in a conventional manner by means of poles 18 and guy ropes 19. It is to be understood that the method and means

of supporting the corners of the canopy may be of any conventional form, many of which are in common use at the present time.

This invention pertains particularly to the means for giving the canopy a pitch to form a water shed, and such means will now be described more in detail.

As shown in the drawings, the top of the center pole 11 is provided with the usual metal pin 11a projecting through the top of the tent at the peak. Likewise, the poles 18 at the outer corners of the canopy have similar pins 18a, 18a. 20 indicates a rope attached to the pin 11a at one end with the other end attached at 21 to the bridle ropes 22, 22, having their outer ends attached 15 to the pins 18a, 18a.

Fastened to the canopy 13 are one or more loops or rings engaging the rope 20 or the ropes 22 and serving to lift the center of the canopy at one or more points to form peaks or a ridge to cause the water to drain therefrom. For example, as here shown, I provide three of such rings, 30, 31 and 32, arranged in a line along the center of the canopy from front to back. The ring 30 engages the bridle ropes 22, 22 and 25 holds the same together at this point. The rings 31 and 32 engage the rope 20. The ring 32 is preferably fastened on a strap 32a to space it away from the canopy a short distance so the canopy will not be raised too high at this point. 30 34, 34 indicate tighteners carried by the ropes 22, 22 so that the tension may be adjusted as desired.

In the device of Figs. 3 and 4 I have shown the supporting ropes under the canopy. In these views similar parts are indicated by the same reference numerals augmented by 100. 35

110 indicates the tent with the center pole 111 and the frame 112.

113 indicates the canopy or awning with its 40 rear corners 114 and 115 fastened to the corners of the tent. The outer corners of the canopy are held by the poles 118 supported by the guy ropes 119.

In the form of device shown in Figs. 3 and 4 45 the rope 120 corresponding to the rope 20 in the other form is attached to the center pole 111 somewhat below the top. It is to be understood, however, that in either form the rope 20 or 120 may be attached to either the pin 11a, or 111a 50 at the top of the pole or else to the pole itself some distance below the pin. As in the other form the rope 120 has its outer end attached at 121 to the bridle ropes 122 having their outer ends attached to the pins 118a at the tops of 55

the poles 118. The seam where the canopy 113 is attached to the roof of the tent is indicated by 200 and it will be seen that this seam is preferably somewhat V-shaped so that the canopy 113 is attached to the roof at a point somewhat higher than at the corners. The suitable opening in the roof is provided at 201 just under this canopy seam for the rope 120 to pass through. The tighteners 134 provided in the bridle ropes may be used to tighten the ropes and this will form a ridge along the canopy under the rope 120. This ridge at the outer extremity of the canopy will divide and follow the bridle ropes 122.

15 While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

20 25 What I claim as new, and desire to secure by Letters Patent is:

1. In combination with a tent having a peak; a substantially horizontal polygonal canopy at one side of the tent with two outer corners supported by poles, the peak of the tent extending higher than the canopy; a rope with one end attached to the tent at or near the peak at an elevation above the canopy and the other end attached to bridle ropes connected to the poles supporting the outer corners of the canopy; and means for supporting a portion of said canopy from said ropes in raised position to produce a pitch in said canopy to shed rain water therefrom.
- 30 35 40 2. A tent structure according to claim 1, in

which the bridle ropes are connected to the upper end of the poles supporting the outer corners of the canopy.

3. A tent structure according to claim 1, in which the means for supporting a portion of the canopy from the ropes includes a member having one portion connected to said ropes and the other portion connected to said canopy.

4. A tent structure according to claim 1, in which a portion of the canopy is supported from the ropes in raised position by placing the canopy over a portion of said ropes.

5. In combination with a tent having a center pole; a substantially horizontal polygonal canopy at one side of the tent with two outer corners supported by poles, the center pole of the tent extending higher than the canopy; a rope with one end attached to the center pole of the tent at an elevation above the canopy and the other end attached to bridle ropes connected to the poles supporting the outer corners of the canopy; and means for supporting a portion of said canopy from said ropes in raised position to produce a pitch in said canopy to shed rain water therefrom.

6. A tent structure according to claim 5, in which the bridle ropes are connected to the upper end of the poles supporting the outer corners of the canopy.

7. A tent structure according to claim 5, in which the means for supporting a portion of the canopy from the ropes includes a member having one portion connected to said ropes and the other portion connected to said canopy.

8. A tent structure according to claim 5, in which a portion of the canopy is supported from the ropes in raised position by placing the canopy over a portion of said ropes.
